UNITED STATES PATENT OFFICE.

A. H. MILLER, OF LA PORTE, INDIANA.

IMPROVEMENT IN APPARATUS FOR EVAPORATING SUGAR.

Specification forming part of Letters Patent No. **33,593**, dated October 29, 1861.

To all whom it may concern:

Be it known that I, AARON H. MILLER, of La Porte, in the county of La Porte and State of Indiana, have invented certain new and useful Improvements in Sugar-Evaporators; and I do hereby declare that the following is a full and exact description thereof, reference being had to the accompanying drawings, and to the letters of reference marked thereon.

Figure 1 is a perspective view. Fig. 2 is longitudinal vertical section of the furnace.

A is the evaporator, and is divided into two compartments, 1 and 2, by the strip e. The evaporator is supported at a suitable height (depending upon the size of the furnace) from the floor or ground by the legs a.

B is the furnace, as here represented a parallelopipedon in form.

b are the supports or legs of the furnace, and are cleft at the bottom, so as to receive the caster-rollers c.

d are tracks upon which the casters roll.

In operating my invention the juice is made to fill both sides of the evaporator A. The furnace B is then rolled under one of the compartments, (see Fig. 1,) and the fire, as intense as needed, causes the juice in the com-

partment immediately over the furnace to boil very rapidly until evaporated as desired, either for sugar or molasses. The furnace now is rolled over the track d and on rollers e from under the one apartment until it comes immediately under the other one. The boiled juice is then turned off from the first compartment, which is then resupplied. Thus, by alternately rolling the furnace back and forth, the process of evaporating can be continued as long as may be wished without any waste of time, and the empty compartment can be readily cleansed of any adhering impurities.

Having thus fully described the construction and operation of my invention, what I claim as new, and desire to secure by Letters Patent, is—

An apparatus for evaporating saccharine liquids, so constructed that the fire-grate or furnace is adjustable under the pan to be heated, as herein set forth.

AARON H. MILLER.
